Primary Examiner — Prabhakar Deshmukh(74) *Attorney, Agent, or Firm* — Young & Thompson(57) **CLAIM**

The ornamental design for a controller for electronic device, as shown and described.

DESCRIPTION

FIG. 1 is a perspective view of front, top and right side of a controller for electronic device showing my new design; FIG. 2 is a perspective view of rear, bottom and left side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion 9 shown in FIG. 6 thereof; and,

FIG. 10 is another enlarged view of portion 10 shown in FIG. 7 thereof.

The broken lines form no part of the claimed design. The dot and dashed lines form no part of the claimed design and mean boundaries between the claimed portion and non claimed portion.

1 Claim, 8 Drawing Sheets(56)
